UNITED STATES PATENT OFFICE

2,200,876

CRANKCASE FLUSHING MACHINE

Carl F. Ehinger, Cleveland, Ohio, assignor, by
mesne assignments, to Paul B. Hunt, Cleve-
land, Ohio

Application April 7, 1936, Serial No. 73,141
Renewed October 19, 1939

3 Claims. (Cl. 285—44)

This invention relates to improvements in mechanisms for flushing the crankcases of internal combustion engines and for removing used and impure lubricating oil and collections of sludge or other impurities deposited in the crankcases of engines.

Internal combustion engines and particularly the engines of motor vehicles accumulate sludge and other impurities within the crankcases thereof in service. These deposits of impurities are not dislodged by the mere act of draining the crankcase to change the oil, and if the impurities are not removed they will mingle with the new charge of oil introduced into the crankcase and thus immediately contaminate the new oil with impurities. According to my invention, I provide a continuous circulation of flushing oil or fluid through the crankcase by the employment of a vacuum pump and circulating pipes and I thoroughly clean the crankcase by forcibly circulating cleaning fluid through the crankcase in a path different from the normal flow of lubricating oil in the engine.

It is among the objects of my invention to provide a simple efficient mechanism adapted to circulate flushing oil or fluid through the crankcase of an internal combustion engine effectively to clean the crankcase. Another object is to provide a unitary, portable mechanism of this type. Another object of my invention is to provide an apparatus embodying means for circulating the flushing oil from the crankcase through a transparent trapping receptacle so that the removal of impurities from the crankcase may be seen by the operator of the device and by the owner of the vehicle. Another object is to provide a trap for accumulating sludge and other impurities which can be readily removed and cleaned. A further object of my invention is to provide a connector or coupling member whereby the device can be connected with the drain opening of the crankcase, the connector being arranged to fit crankcase openings of a wide range of sizes without requiring any special adapters or fittings.

Further objects and advantages of my invention will become apparent from the following description of a preferred form thereof, reference being made to the accompanying drawings. The essential characteristics are summarized in the claims.

Briefly, a flushing machine according to my invention preferably comprises a unitary portable structure including a tank for the reception of the flushing oil, a motor driven suction

pump, pipe lines connecting the tank with the suction pump or the crankcase with the pump, a supply pipe leading from the pump to the inlet opening in the crankcase, and an intermediate transparent trapping receptacle through which all impure oil passes before entering the pump or crankcase. The trapping receptacle preferably contains a filtering screen which may be enclosed in a removable cloth filtering bag, the bag being preferably renewed after each filtering operation. By means of a three-way valve in the circulating lines of the pump, the suction pipe may be first connected with the supply tank and afterward with the crankcase and a pipe leading from the valve to the intermediate receptacle may be opened to provide a continuous circulation of pure flushing oil to the pump and crankcase.

The invention also includes the provision of an intermediate two compartment transparent receptacle which is constructed to form a trap for the sludge as fast as it is carried away from the engine crankcase, the transparent walls of which permitting the operator to witness the accumulation of sludge therein, and also to know when the crankcase has been thoroughly cleansed by the passage of pure oil through the transparent compartment. The trap may be easily removed from the receptacle for cleaning.

In the drawings, Figure 1 is a front elevation of a flushing apparatus embodying my invention; Figure 2 is a side elevation of the apparatus shown in Figure 1; Figure 3 is a plan view thereof; Figure 4 is a sectional view of a three-way valve which controls the circulation of the flushing oil or other cleansing fluid; Figure 5 is a vertical section through the sediment trap and receptacle and illustrating the filter screen without a filtering bag; Figure 6 is a fragmentary vertical section as indicated by the line 6—6 on Figure 7; Figure 7 is a transverse section as indicated by the line 7—7 on Figure 5; Figure 8 is a vertical section as indicated by the line 8—8 on Figure 7 and showing the filtering bag in place on the filtering screen; Figure 9 is a diagrammatic elevation showing the device in use; and Figures 10 and 11 are sectional views on an enlarged scale of the coupling member for connecting the suction pipe of the machine to the crankcase of the internal combustion engine.

As shown in the drawings, the tank 1 which is adapted to contain the flushing oil is vertically mounted upon an angular truck frame 2 which is provided with wheels or casters so that it can readily be transported from place to place and

can be moved to a convenient position for operation upon the crankcase of a motor car. An electrical motor 4 and a suction pump 5 are also mounted on the frame 2, the motor and pump shafts being operatively connected by means of any suitable coupling 8.

The fluid connections include an outlet pipe 10 leading from the pump and adapted to be inserted in the filler opening of the crankcase 20, while the intake side of the pump may be connected through the pipe 13 and the sediment receptacle or trap to the three-way valve 11 which functions to place the pump in communication either with the supply tank 1 through 15 the pipe 9 or with the suction pipe 12 which is adapted to be inserted in the drain opening of the crankcase.

When the electric motor is operated with the connections between the pipes 9 and 13 open, 20 clean flushing oil will be drawn from the supply tank and discharged into the filler opening of the crankcase through the hose 10 which is positioned as shown in Figure 9. After the crankcase is filled with clean flushing oil, the three-way valve 11 is turned to the position shown in Figure 4 to close the pipe 9 leading from the supply tank and to open communication with the suction pipe 12 leading from the drain opening in the bottom of the crankcase. With the valve 30 in the position shown in Figure 4, a continuous circulation of flushing oil takes place from the pump 5 through the outlet pipe 10, into the crankcase of the engine, through the crankcase of the engine from which it is drawn through the suction pipe 12, through the sediment trap and back to the suction pump.

In order to remove the sludge and other impurities from the circulating oil as it is being circulated through the crankcase, I have provided 40 the intermediate trap receptacle illustrated particularly in Figures 5 to 8 inclusive. As shown in Figure 5, fluid flowing to the three-way valve 11 is discharged therefrom into the lower compartment 15 of the sediment trap which is separated from the upper compartment 16 by means 45 of a partition 17. The fluid discharged into the lower compartment rises through the filtering screen 19 and into the central pipe or passage 18 and is discharged into the upper compartment 50 16 from which point it is drawn off through the pipe 13 leading to the pump where it is again circulated through the pipe 10 into the inlet opening 20 of the crankcase.

A removable filtering bag 19a made of fine mesh 55 gauze or other suitable filtering fabric may be slipped over the filtering screen 19 as shown in Figure 8 in order to most effectively remove the solid particles from the flushing oil. The bag may conveniently be held in place by an elastic 60 band or string 19b at the open end thereof, which contracts the bag about the pipe 18 in the region immediately above the top of the screen 19. In use the flow of oil from the compartment 15 upwardly through the pipe 18 causes the bag to 65 be held firmly against the screen 19, the screen functioning to support the bag and prevent it from being collapsed by the pressure of the oil. Preferably each filtering bag is used only once. The circulation of flushing oil may be started with 70 a clean white bag and at the end of the flushing operation, the dirty bag can be removed and examined to demonstrate the amount of impurities removed from the crankcase to the owner of the car which is being serviced.

75 Preferably the lower and upper chambers 15

and 16, respectively, of the trap or receptacle comprise large glass bulbs having threaded portions 30 adapted to engage internally threaded metallic cups 31. The cups 31 are arranged back to back and may be conveniently welded to the partition member 17 which is formed with bores or passageways communicating with the inlet and discharge pipes 12 and 13.

In Figures 10 and 11 of the drawings I have shown the coupling device for securing the pipe 10 to the drain opening of the crankcase. This form of connector may comprise a body portion indicated generally at 41 having an axial bore 42 and an angularly intersecting fluid passageway 43 terminating in the internally threaded portion 44 for connection with the suction pipe 12. In the region below the intersection of the passageways 43 and 42, the passageway 42 is threaded as indicated at 44 to receive a correspondingly threaded plug 45 which is threaded therein and which supports a hook member 46 extending upwardly through the axial passageway 42 and having a bent end portion 47 which is adapted to engage the inner wall of the crankcase 48 of the internal combustion engine.

At the upper end of the body portion 41, another hook member 49 is secured preferably by threading into an internally extending boss 50 disposed within the passageway 42. This hook member has a bent end portion 51 similar to the end portion 47 of the hook portion 46 which is likewise adapted to engage the inner surface of the wall of the crankcase 48, the two hook members extending in opposite directions when the device is in use as shown in Figure 5.

To make a leak proof joint between the crankcase and the coupling member, I have provided the exterior of the body member 41 with a threaded portion 52 on which is threaded a knurled sleeve or nut 53 which supports at its upper end 40 a flanged disc 54 adapted to retain a gasket or washer 56 of a suitable sealing material. By screwing the nut member 53 upwardly along the threads 52, the gasket 56 may be forcibly engaged with the under surface 57 of the wall of the 45 crankcase, the coupling member being retained in engagement with the crankcase by the hook members 51 and 47.

In order to provide for the easy attachment and removal of the coupling member, the hook member 46 is mounted for rotation with the block 45 so that when the block 45 is turned through an angle of 180 degrees by means of the handle 60 the end 47 of the hook member 46 is rotated to a position where it lies closely adjacent the end portion 51 of the hook member 49 as shown in Figure 10 of the drawings. In this position and with the nut 53 screwed downwardly as indicated in Figure 10, the device can readily be inserted within the drain opening of a crankcase, and to 65 secure the device therein it is only necessary to turn the handle 60 from the position shown in Figure 10 to the position shown in Figure 11 thereby separating the end portions of the hook members and at the same time screwing the plug 65 45 inwardly into the end of the body portion 41, thus compressing the gasket 51 and making a tight joint between the plug member and the end of the body member. Thereafter the sleeve member 53 is screwed upwardly to the position 70 shown in Figure 11 to compress the gasket 56 against the lower surface of the crankcase to make a tight connection between the suction hose 12 and the crankcase of the internal combustion engine.

It will be seen that by means of my connectors it is possible rapidly and easily to make a leak proof connection with the crankcase of an internal combustion engine, that no adapters or special fittings are required, and that my connectors will fit drain openings of a wide range of sizes without change.

It will be apparent to those skilled in the art that I have provided a simple, inexpensive, efficient and portable device by means of which the collections of sludge adhering to the inner walls of the crankcase may be forcibly washed away, and deposited in a transparent trap where they can be seen as fast as removed. My device circulates the cleaning or flushing fluid in a path different from the ordinary path of lubricant in the engine, and by reason of the suction connection the flushing fluid is circulated with sufficient velocity efficiently to clean the crankcase and remove substantially all sludge and other deposits therefrom. By reason of the transparent trapping receptacle, the results of the cleaning operation can be seen and it can readily be observed when the fluid becomes free from impurities and the crankcase has become clean. The collected impurities may be readily removed from the trapping receptacle so that the entire apparatus is substantially self-cleaning.

Various modifications of my invention will be apparent to those skilled in the art to which it relates. It is therefore to be understood that my patent is not limited by the foregoing description of preferred forms of my invention or in any manner other than by the appended claims 35 when given the range of equivalents to which my patent may be entitled.

I claim:

1. A fluid connection adapted for engagement with a receptacle having a drainage opening, comprising a body portion, a hook member rigidly mounted on said body portion, a second hook member rotatably mounted within said body portion and adapted in one position of adjustment to lie alongside said first mentioned hook member

and in another position of adjustment to extend in a direction away from said first mentioned hook member, both of said hook members being adapted to project within the drainage opening and to engage the inner wall of the receptacle adjacent the drainage opening, a sealing washer disposed on the exterior of said body portion, and means for urging said sealing washer into sealing engagement with the exterior surfaces of said receptacle adjacent said drainage opening. 5 10

2. A fluid connection adapted for engagement with a receptacle having a drainage opening, comprising a body portion, a hook member rigidly mounted on said body portion, a second hook member rotatably mounted on said body portion 15 and adapted in one position of adjustment to lie alongside said first mentioned hook member and in another position of adjustment to extend in a direction away from said first hook member, both of said hook members being adapted to project 20 within the drainage opening and to engage the inner wall of the receptacle adjacent the drainage opening, and sealing means engageable with the exterior surfaces of said receptacle adjacent said drainage opening. 25

3. A fluid connection adapted for engagement with a receptacle having a drainage opening, comprising a body portion, a hook member rigidly mounted on said body portion, a second hook member rotatably mounted on said body portion 30 and adapted in one position of adjustment to lie alongside said first mentioned hook member and in another position of adjustment to extend in a direction away from said first hook member, both of said hook members being adapted to project 35 within the drainage opening and to engage the inner wall of the receptacle adjacent the drainage opening, a sealing washer disposed on the exterior of said body portion, and screw means for urging said sealing washer into sealing 40 engagement with the exterior surfaces of said receptacle adjacent said drainage opening.

CARL F. EHINGER.
